COLLISION MEASURING APPARATUS

Roger Dean Stephenson, 18 East Drive,
Columbia, Mo. 65201

Filed Sept. 20, 1968, Ser. No. 13,632

Term of patent 14 years

Int. Cl. D19—08

U.S. Cl. D25—1

FIG. 1 is a perspective view of a collision measuring apparatus showing my new design;

FIG. 2 is a top plan view;

FIG. 3 is a side elevational view of the device seen in FIG. 2; and

FIG. 4 is a front elevational view of the device seen in FIG. 2.

I claim:

The ornamental design for a collision measuring apparatus, as shown and described.
